UNITED STATES PATENT OFFICE.

GEORGE W. WADDELL, OF SYRACUSE, INDIANA.

GOLF-BALL EJECTOR.

1,402,026.

Specification of Letters Patent. Patented Jan. 3, 1922.

Application filed November 25, 1919. Serial No. 340,501.

To all whom it may concern:

Be it known that I, GEORGE W. WADDELL, citizen of the United States, residing at Syracuse, in the county of Kosciusko and 5 State of Indiana, have invented certain new and useful Improvements in Golf-Ball Ejectors, of which the following is a specification.

This invention relates to a ball ejector for 10 use in the cups or holes positioned on the greens of golf courses.

In the game of golf the course played over is divided into a series of holes separated from each other by varying distances 15 in which natural or other impediments to play may be located. The player drives a ball from a teeing platform adjacent one hole toward another hole and the object is to reach the hole in the shortest number of 20 playing strokes possible. On arriving adjacent the hole there is a relatively smooth grass plot forming what is termed a green and near the center of which is located a hole or cup, the object of the player being to eventually roll the ball into this hole or cup 25 by striking the ball with the proper golf club. Each hole is marked, as a general rule, by a standard fixed on a staff and the staff of which extends down into the hole so that 30 prior to making any effort to putt the ball into the hole the player must see that the staff is removed so as to form no obstruction to the entrance of the ball. After the staff is removed and the player knocks the 35 ball into the hole he must reach into the hole or cup placed in such hole and remove his ball in order to continue playing.

As a group of players approach a hole 40 one of the caddies accompanying them usually runs forward and removes the marker staff from the hole, replacing it after the players have "holed in" and the balls have been taken out of the cup.

It is one of the objects of the present invention to provide a ball ejector which may 45 be placed within the hole or cup defining the hole and may be operated to eject the balls from said hole or cup.

A further feature of the invention is to 50 arrange the same so that the marker staff may be removed from the hole when desired and on replacing the same the balls will be automatically ejected from the hole or cup.

Another feature is to provide a device for 55 ejecting the balls from the hole or cup which is so constructed that a false bottom auto-

matically raises the balls to the surface level and rolls them out without any effort on the part of the caddie other than merely replacing the marker staff in the hole.

60

A still further feature resides in providing such a device as is above mentioned which cooperates with the marker staff in such a manner as to form a support therefor and yet leaves no projections above the 65 surface of the green when the marker staff is removed and which might form obstructions to the entrance of the ball into the hole or cup.

In the drawings:

70

Figure 1 is a phantom perspective showing the ball ejector located in a cup,

Fig. 2 is a vertical section centrally through the ball ejector and cup and showing the same in its normal position,

75

Fig. 3 is a view similar to Fig. 2, but showing the position of the false bottom immediately on insertion of the marker staff,

Fig. 4 is a transverse section on the line 80 4—4 of Fig. 2, and Fig. 5 is a transverse section on the line 5—5 of Fig. 2,

Fig. 6 is a perspective view of the false bottom and its attendant parts removed from the body of the ejector,

85

Fig. 7 is a disassembled view of one half of the ejector body and attendant parts.

In detail the ejector, as illustrated is adapted to set either into a cup 1 of cylindrical form such as is usually placed in the 90 holes on golf greens or may be placed directly into a cylindrical hole, in which case its operation as will be hereinafter described serves to clean the hole of loose earth as each player or group of players leave the 95 green. The cup 1 is provided with a drain outlet 2 in the bottom thereof.

The ejector proper includes duplicate castings A and B one of which is clearly shown in Fig. 7 and comprises semi-circular 100 base and head members 3 and 5 respectively, said base member being provided with a drain opening 7 registering with the drain outlet 2 in the cup 1. The base and head 3 and 5 are connected by a body 8; the two 105 castings A and B have matching abutting faces and are held together by bolts 9 extending through holes 10 and carrying nuts 11. The body 8 is substantially rectangular in cross section and is offset with respect 110 to the center of the head and base of the ejector. The assembled castings A and B are

bored vertically as at 12 on the common center line of the heads 5 and bases 3, and a boss 13 extends above the level of the head 5 and surrounds the bore 12 to prevent water and dirt from entering the same as would be the case if the mouth of the bore 12 remained on a level with the upper surface of the head 5. Each half A and B is provided with a vertical recess 14 near the periphery of the head 5 and a boss 15, the two halves when assembled forming a vertical chamber 16 of rectangular cross section and bosses 15 cooperating to perform the same function as bosses 13, namely, to prevent the entrance 15 of dirt and water into said vertical chamber.

In each casting A and B, the body 8 thereof is recessed on the abutting face between the bore 12 and chamber 16 and adjacent the head 5 to form a cut-out 17 of oblong form 20 and having its greater length vertically; the rear face 18 of each of these cut-outs is counter-recessed as at 19 and 20 and these cooperating cut-outs and recesses combine, when the two castings A and B are in assembled relation, to form a housing for a pinion 21 the hub 22 of which rides in the counter recess 19 and the spindle 23 of which rides in the counter-recess 20 of each half or casting A and B. The pinion 21 is thus 30 confined to rotation in the said housing formed by the cooperating cut-out and recess but may rise and fall vertically to a limited extent for purposes to be hereinafter set forth. Teeth 24 on said pinion project 35 into the bore 12 and vertical chamber 16. In the bottom of the vertical bore 12 is a short spiral spring buffer 25. A false bottom 26 of frusto-conical form provided with a downwardly projecting boss 27 40 aligned with the bore 12 carries a dependent vertical rack 28 having teeth 29 which, when said false bottom is in place mesh with the teeth 24 on the pinion 21 as the rack 28 is offset from the center of the false bottom 45 26 sufficiently so that the rack 28 enters the vertical chamber 16. Adjacent the top of the rack 28 the teeth are interrupted for a space as shown at 30, the thickness of the rack at this point being equal to the normal thickness of the rack less the depth of the teeth. When the rack and false bottom 26 are in position they normally occupy positions shown in Fig. 2. A marker C provided with a staff 31 carries on its lower 50 end a cylindrical rack 32, the teeth 33 of which are of the right pitch to engage the teeth of the pinion 21 and adjacent the upper end of the rack 32 the teeth 33 are interrupted for a space as shown at 34, the dimensions of the space 30 of the rack carried by the false bottom and the space 34 of the cylindrical rack carried by the staff 31 are equal. At the top the staff 31 is provided with arms 35 and 36 or any other 60 suitable means forming a display signal to

indicate the location of the hole. The lower end of the rack 32 butts against the buffer spring 25 in descending into the bore 12.

The operation of the ejector is as follows:—Suppose the parts to be assembled 70 in their respective positions as shown in Fig. 2 and a group of players is about to approach the green with the object of driving the balls into the cup 1. The caddie precedes the players and removes the staff 75 31 from the hole and in so doing the rack teeth 33 of the rack 32 engage the pinion 21 and rotate the same but the position of the false bottom is such that the interrupted space 30 of the rack 28 carried by the false 80 bottom is directly opposite the pinion and as the staff 31 is withdrawn it merely raises the pinion bodily in its recess and rotates it freely against the interrupted portion 30 of said rack 28. However, suppose that the 85 players have "holed in" and the balls are in the position shown in the cup 1 of Fig. 2 and the caddie or players desire to remove the same. The staff 31 having been removed is reinserted in the central bore 12 90 through the boss 27 in the false bottom 26 and the rack 32 engages with the pinion; the pinion 21 has bodily dropped in its recess sufficiently so that its teeth engage the first tooth of the rack 28 and the weight 95 of the staff 31 or the pressure placed thereon by the persons inserting the same is sufficient so that the teeth 32 engaging the pinion roll it in the direction indicated by the dotted arrow in Fig. 3 and raise the false 100 bottom 26 above the surface of the green as shown in Fig. 3 carrying with it the balls contained in the cup 1 and which offer no obstruction to the movement of the false bottom 26 due to the fact that the balls 105 are spherical in form and roll easily against each other and against the sloping surface of the false bottom 26 and the vertical side wall of the cup 1. After the ejector has been thus operated to eject the ball and 110 the false bottom 26 has risen to its maximum height and the staff 31 of which the rack 32 is a part has descended and butted against the spring 25 it rests with its interrupted space 34 in such a position that the 115 teeth of the pinion 21 do not engage with the teeth of the rack 32 and the false bottom 26 guided on the staff 31 therefore returns by gravity to the normal position shown in Fig. 2, the rack 28 merely revolving the pinion 21 in its housing. If desired a spring buffer similar to the spring buffer 25 may also be located in the bottom of the vertical chamber 16 to receive the end of the rack 28. A drain 35 is provided in the head 5 so that water entering the top of the cup 1 will drain on down through the drains 2 and 7. 120

It will be seen from the foregoing that I have provided a device which may also be 130

- used in holes on golf courses where the holes are not provided with cups 1 and each operation of the ejector will not only carry with it the balls contained in the hole but 5 will also serve to keep the walls of the holes in proper condition and carry away the loose dirt. This is a particularly important feature even with the holes in which cups 1 are used as the upper edge or mouth of the cup 10 1 is usually depressed beneath the surface of the ground so as to form a rolling edge around the hole and it is necessary that this edge be kept, at all times, in proper condition to permit the entrance of the balls. It 15 is to be noted that when the staff 31 is removed there is no part of the device which projects above the top of the cup 1 to offer obstruction to the entrance of the balls, thus leaving a clear playing field around the cup. 20 Having thus described the invention, what is claimed as new is:
1. Means for removing balls from a golf hole comprising a marker staff insertable in and removable from the golf hole, an ejector 25 normally housed within the golf hole, and cooperating means upon the staff and within the hole operable by insertion of the marker staff whereby the ejector will be lifted from the hole and remove the balls. 30 2. Means for removing balls from a golf hole comprising a marker staff insertable in and removable from the golf hole, an ejector normally housed within the golf hole, cooperating means upon the staff and 35 within the hole operable by insertion of the marker staff whereby the ejector will be lifted from the hole and remove the balls, and means whereby after the ejector has been raised the last-mentioned means will be 40 freed and the ejector permitted to re-enter the hole.
  3. Means for removing balls from a golf hole comprising a marker staff insertable into and removable from the golf hole, an ejector normally housed within the golf hole, operating mechanism comprising a member carried by the ejector, a cooperating member held within the golf hole, and means carried by the marker staff to actuate 50 the operating mechanism upon insertion of the staff whereby the ejector will be raised from the golf hole and remove the balls, said operating mechanism being arranged to release the ejector and permit its return when 55 the marker staff has been fully inserted.
  4. Means for ejecting golf balls from holes, comprising a marker staff, a marker staff support including ball ejecting means, and mechanism connecting the marker staff 60 and said support whereby movement of the staff in said support operates the ball ejecting means.
  5. Means for ejecting golf balls from holes, comprising a marker staff carrying a 65 rack, a false bottom for said hole also carrying a rack, and means for engagement with the two racks to place the same in geared relation on downward movement of said marker staff.
  6. Means for ejecting golf balls from 70 holes, comprising a marker staff carrying a rack, a false bottom for said hole also carrying a rack, and means gearing the two racks for upward movement of the false bottom rack on downward movement of the 75 marker staff rack.
  7. Means for ejecting golf balls from 80 holes, comprising a marker staff carrying a rack, a false bottom for said hole also carrying a rack, and means engaging the teeth of both racks on movement of the marker staff rack in one direction.
  8. Means for ejecting golf balls from 85 holes, comprising a marker staff carrying a rack having interrupted teeth at one point, a false bottom carrying a rack having interrupted teeth at a similar point, and a bodily movable pinion confined between said racks for engagement with both racks on movement of the marker staff rack in one direction.
  9. Means for ejecting golf balls from 90 holes, comprising a marker staff having a rack having interrupted teeth at one point, a false bottom carrying a rack also having 95 interrupted teeth at one point, and a bodily movable pinion normally engaging the teeth of the rack carried by the false bottom and moved bodily out of engagement with said teeth on movement of the marker staff rack 100 in one direction and rotating in engagement with said false bottom rack to move the false bottom when said marker staff rack is moved in an opposite direction.
  10. Means for ejecting golf balls from 105 holes, comprising a removable marker staff, a rack carried by said staff and having an interruption at its upper end, a rising and falling false bottom for said hole, a rack carried by said bottom and having an interruption at its upper end, and a bodily movable pinion for engagement with both racks, removal of said marker staff bodily moving said pinion out of engagement with said 110 false bottom rack to permit independent movement of said marker staff rack and replacement of said marker staff rotating said pinion in engagement with said false bottom rack to move the latter in a direction opposite to the movement of said marker staff 115 rack.
  11. Means for ejecting golf balls from 120 holes, comprising a cylindrical ball receptacle, and a movable false bottom ejector member in said receptacle and forming a marker staff support, and a marker staff for insertion in said support and mechanism connecting the said ejector and staff to momentarily raise and lower said false bottom to eject 125 balls from said receptacle.

12. Means for ejecting golf balls from holes, comprising a body member located in a hole and having a bore receiving a removable marker staff provided with a rack, a 5 chamber in said body receiving a second rack carrying a false bottom, and means connecting the two racks for movement in opposite directions on replacing of said marker staff.
- 10 13. Means for ejecting golf balls from holes, comprising a body member located in a hole and having a bore receiving a removable marker staff provided with a rack, a chamber in said body receiving a second rack 15 for reciprocal movement only and carrying a false bottom, and means connecting the two racks for movement in opposite directions on replacement of said marker staff.
14. Means for ejecting golf balls from 20 holes, comprising a body member located in a hole and having a bore receiving a removable marker staff provided with a rack, a chamber in said body receiving a second rack carrying a false bottom and a bodily and rotatably movable pinion ratchet member 25 connecting the two racks for simultaneous movement in opposite directions on replacing said marker staff to raise said false bottom above the ground level and eject the balls.
- 30 15. Means for ejecting balls from holes comprising a false bottom of frusto-conical form, and rack and pinion means for automatically raising said bottom above the mouth of the hole to cause said frusto-conical surface to roll the balls away from the 35 mouth of the hole.
16. Means for ejecting balls from holes, comprising a false bottom, and rack and pinion means for raising said false bottom above the mouth of said hole to cause the 40 same to expel the balls carried thereby, and removable marker staff means having a rack for engaging said pinion opposite to the first-mentioned rack for moving said bottom only on replacement of said marker staff. 45
17. Means for ejecting golf balls from holes, comprising a body member having a vertically positioned bore and a chamber parallel therewith, said body member having a recess between the bore and chamber at the 50 top, a rotatable pinion bodily movable in a vertical plane in said recess, a false bottom having a rack in said chamber with interrupted teeth at the point normally opposite said pinion, and a marker staff having a rack 55 seating in said bore and with interrupted teeth opposite said pinion, removal of said marker staff rack meshing the same with said pinion to bodily move the latter upwardly and rotate it out of engagement with the teeth of said false bottom rack and replacement of said marker staff rack rotating said pinion into engagement with said false bottom rack to raise the latter. 60

In testimony whereof I affix my signature. 65
GEORGE W. WADDELL. [L. s.]
